HEAT TRANSFER RESISTING MEANS FOR
CARBURETORS

Walter H. Weber, Detroit, Mich., assignor to Detroit Lubricator Company, Detroit, Mich., a corporation of Michigan

Application January 24, 1944, Serial No. 519,416

3 Claims. (Cl. 261—1)

This invention relates to new and useful improvements in carburetors for supplying fuel to an internal combustion engine.

In the operation of carburetors using gasoline or other radially vaporizable fuels, it may occur that the heat of the engine conducted to the carburetor float chamber will cause the fuel therein to boil, and thus upset the uniform rate of supply of fuel to the mixing chamber. In some cases, this will even cause a vapor lock preventing operation of the engine. It is, accordingly, the object of this invention to provide means to reduce the rate of heat transfer from the engine to the carburetor fuel container or reservoir sufficiently so that vapor locking and boiling will not occur.

The invention consists in the improved construction and combination of parts to be more fully described hereinafter and the novelty of which will be particularly pointed out and distinctly claimed.

In the accompanying drawing, to be taken as a part of this specification, there is fully and clearly illustrated a preferred embodiment of the invention, in which drawing:

Figure 1 is a view in vertical central section of a carburetor attached to an engine and having the heat transfer blocking means of the invention;

Fig. 2 is a plan view of the outlet end portion of the carburetor;

Fig. 3 is a view in side elevation of the outlet end portion of the carburetor, and

Fig. 4 is a view in section of the outlet end portion of the carburetor, taken on the line 4—4 of Fig. 2.

Referring to the drawing by characters of reference, 1 designates generally the body member of a carburetor having a mixture passageway 2 with an air inlet 3 and an outlet 4. The member 1 is preferably a die casting having integrally cast therewith a constant level fuel reservoir 5 which, by reason of its rigid connection to the body member 1, is in intimate heat exchange relation therewith. The reservoir 5 has the usual liquid inlet 6 for liquid fuel, such as gasoline. The liquid level in the reservoir 5 is controlled by a float member 7 which is operatively connected to a valve 8 controlling flow into the reservoir 5 from the inlet 6. The reservoir 5 is connected to the mixture passageway 2 by a fuel conduit 9 having a calibrated inlet port 10 below the reservoir liquid level. The conduit 9 has a portion 11 above the reservoir liquid level and has an outlet or nozzle 12 discharging into the passageway 2 within the throat of a Venturi tube 13 positioned within the passageway 2. The usual butterfly type throttle

valve 14 is provided to control the discharge of fuel mixture from the carburetor outlet 4.

The outlet end portion of the passageway 2 is formed by a thin wall tubular conduit member 15 of low heat conducting material, such for example as stainless steel. The member 15 fits within an internal annular end recess in the body member 1 and has its inner end edge abutting a shoulder to limit its inward movement. The conduit member 15 extends beyond or projects externally from the body member 1 and has its exterior end provided an out-turned lateral flange 16. The body member 1 may be provided with legs or fins 17 which extend longitudinally of the exterior portion of the member 15 and back or reinforce the flange 16. Surrounding the member 15 and projecting laterally from the outlet end portion of the body member 1, there is a hollow supporting flange 18 which seats on or against the block or manifold 19 of the engine to support the carburetor. The flange 18 has a laterally extending plate member 20 which is spaced from the block 19 by a peripheral wall 21 which, together with the plate member 20, provides an inverted cup like member having its rim, i. e. the edge of the wall 21 seating on the block 19. Through the plate member 20 there are air outlet apertures 22 for discharge of air from the interior of the hollow flange. The wall 21 is provided with a plurality of apertures or slot openings 23 for the inflow of air to the interior of the hollow flange. The openings or apertures 22 and 23 cooperate to provide for cooling air flow through the hollow flange and in heat abstracting relation to the exterior surface of the projecting portion of the conduit member 15. The plate member 20 also has openings 24 therethrough positioned adjacent the flange wall 18 and in which are positioned bushings 25 of a length to extend flush with the flange 16 and also flush with, or slightly beyond, the rim of the wall 21. The bushings 25 are also each preferably provided with an end flange 26 which seats against and is backed by portions of the wall 21. The bushings 25 are preferably of low heat conducting material, such as stainless steel, and receive bolts or studs 27 which serve to clamp and secure the carburetor to the block 19.

It will be apparent from the foregoing description that the reservoir 5 is protected against the conduction of engine heat through the walls of the body member 1. Not only does the heat flow resisting member 15 cut down the rate of heat conduction from the block 19, but in addition this member 15 is cooled by air flow entering the hollow flange through the openings 23 and dis-

charging through the openings 22. This air flow, in addition, serves to cool the flange plate member 20, thereby further reducing conduction of heat from the block 19.

What is claimed and is desired to be secured by Letters Patent of the United States is:

1. In a carburetor, a body member to be secured to an engine and having a mixture passageway with an outlet for supplying a combustible mixture to the engine, a liquid fuel reservoir carried by and in heat exchange relation with said body member, a tubular thin wall conduit member of low heat conductivity extending from said body member and forming the outlet portion of said passageway, a hollow flange extending from said body member and surrounding said conduit member, said flange comprising an apertured lateral plate member and a peripheral apertured wall member spaced laterally from and surrounding said conduit member and for abutting engagement with the engine to support said body member on the engine, the apertures in said apertured members providing inlets and outlets for air flow in cooling relation to the exterior of said conduit member, said plate member having bolt receiving openings adjacent said wall member, a bushing member in each opening and having a flange seating against said wall member, said conduit member having a flange in the plane of said bushing member flanges, and reinforcing means extending from said plate member and backing said conduit member flange.

2. In a carburetor, a body member having a passageway portion with a mixture passageway and having a hollow flange for connection of the body member to an engine, a liquid fuel reservoir carried by said passageway portion and communicatively connected to said passageway, said flange including a lateral plate member and a peripheral wall member, said plate member extending around the outlet end of said passageway portion, and a thin wall conduit member of relatively low heat conductivity fitting within said passageway and projecting from the outlet end of said passageway portion and beyond said plate member, said conduit member having its outlet end terminating in

an engine engaging edge, said flange wall member surrounding and being spaced from said conduit member and extending from the outer marginal edge of said plate member and terminating in an engine engaging edge such that said wall member, said plate member and said conduit member provide a channel surrounding said conduit member, said plate member and said wall member each having apertures therethrough for flow of cooling air through said channel to abstract heat from said flange and conduit member so as to resist conduction of engine heat to said reservoir.

3. In a carburetor, a body member having a passageway portion with a mixture passageway and having a hollow flange for connection of the body member to an engine, a liquid fuel reservoir carried by said passageway portion and communicatively connected to said passageway, said flange including a lateral plate member and a peripheral wall member, said plate member extending around the outlet end of said passageway portion, a thin wall conduit member of relatively low heat conductivity fitting within said passageway and projecting from the outlet end of said passageway portion and beyond said plate member, said conduit member having its outlet end terminating in an annular surrounding flange for engagement with the engine, said flange wall member surrounding and being spaced from said conduit member and extending from the outer marginal edge of said plate member and terminating in an engine engaging edge such that said wall member, said plate member and said conduit member provide a channel surrounding said conduit member, said plate member and said wall member each having apertures therethrough for flow of cooling air through said channel to abstract heat from said flange and conduit member so as to resist conduction of engine heat to said reservoir, and reinforcing leg members spaced around said conduit member and projecting from said flange plate member into abutting engagement with said conduit member flange.
